A. KÜNG

AUTOMATIC GUN

Filed May 25, 1925

Inventor

Albert Kung,
By Neuapoth.

Atty

UNITED STATES PATENT OFFICE.

ALBERT KÜNG, OF ZURICH, SWITZERLAND, ASSIGNOR TO THE FIRM WERKZEUG-MASCHINENFABRIK OERLIKON, OF OERLIKON, SWITZERLAND.

AUTOMATIC GUN.

Application filed May 25, 1925. Serial No. 32,626.

To all whom it may concern:

Be it known, that I, ALBERT KÜNG, a citizen of the Swiss Republic, residing at Zurich, Switzerland, have invented an Improvement in Automatic Guns, of which the following description, in connection with the accompanying drawings, is a specification, like characters on the drawings representing like parts.

10 The present invention relates to improvements in automatic guns and provides a cooling arrangement for such automatic guns.

15 The arrangement of cooling ribs transversely or longitudinally arranged on the barrel for cooling the latter is known.

20 The subject matter of the present invention is an arrangement adapted to cause a continuous renewal of the layer of air surrounding the barrel and thereby a more intense cooling action, when the gun is fired. To this end the recoil spring, which is displaced after every shot is arranged as a pump cylinder of a double acting pump the 25 piston of which is formed by a closing ring fixed to the barrel so that a renewal of cooling air is effected with every shot.

25 Preferably closing rings are provided at both ends of the casing enclosing the recoil spring which close the space between the casing and the barrel against the outside. Apertures or slots may be provided in the spring casing through which the inflow and outflow of the air occurs.

35 A constructional example of the subject matter of the present invention is illustrated in the accompanying drawings in which:

Fig. 1 shows part of the automatic gun in an outside view,

40 Fig. 2 is a horizontal section through the automatic gun with the breech cocked.

Fig. 3 is a cross section along line III—III in Fig. 2 and

45 Fig. 4 shows on a smaller scale the complete automatic gun mounted on a gun-carriage.

The automatic gun illustrated is a large bore automatic gun of the known type in which the barrel is stationary and the breech moves relatively to the barrel by the recoil action after every shot and is returned into its initial position by a recoil spring. The barrel 1 is provided with longitudinal ribs 2 and carries the trunnion ring 3 and is 55 screwed into the breech sleeve 4. The cas-

ing 5 is rigidly connected to the breech 6 by means of the breech bars 7 and the intermediate member 8. Closing rings 9 and 10 are provided at both ends of the casing 5, the latter enclosing the recoil spring 13 interposed between the front end of the casing 5 and a ring 11 fixed to the barrel 1.

When carrying out the reciprocating movement of the casing 5 relatively to the stationary barrel under the influence of the recoil action of the shot and of the recoil spring 13 the casing 5 together with the closing rings 9, 10 and 11 form a double acting air pump, of which the casing is the cylinder and the ring 11 acts as piston, whereby air is sucked and expelled through the apertures 12 in the casing. The casing 5 has thus the double function as abutment member of the recoil spring and as cylinder for the cooling arrangement.

The closing rings 9, 10 and 11 are comb-shaped, i. e. they are provided with radial extensions which fit well into the intermediate spaces 2' between the ribs 2 of the barrel so that the total free cross-section 80 between barrel and casing is substantially filled up by these rings.

I claim:

1. In an automatic gun, in combination, a barrel provided with longitudinal ribs, a breech, a casing surrounding said barrel and rigidly connected to said breech, a recoil spring enclosed in said casing and operatively connected to the latter whereby the casing is adapted to carry out a reciprocating movement relatively to the barrel when the gun is fired, and a ring fixed to said barrel intermediate of the ends of said casing and substantially filling up the free cross-section between barrel and casing and 90 acting as stationary piston to the reciprocating casing which acts as an air pump for renewing the air surrounding the barrel and increasing the cooling action.

2. In an automatic gun, in combination, a barrel provided with longitudinal ribs, a breech, a casing surrounding said barrel and rigidly connected to said breech, a recoil spring enclosed in said casing and operatively connected to the latter whereby the 105 casing is adapted to carry out a reciprocating movement relatively to the barrel when the gun is fired, rings provided on both ends of said casing and having extensions that fit into the intermediate spaces between said 110

ribs on the barrel to close the ends of the annular space between the casing and the barrel substantially air-tight, and a ring fixed to said barrel intermediate of the ends of said casing and substantially filling up the free cross-section between barrel and casing and acting as stationary piston to the reciprocating casing which acts as an air pump for renewing the air surrounding the barrel and increasing the cooling action.

3. In an automatic gun, in combination, a barrel provided with longitudinal ribs, a breech, a casing surrounding said barrel and rigidly connected to said breech and provided with apertures, a recoil spring enclosed in said casing and operatively connected to the latter whereby the casing is adapted to carry out a reciprocating move-

ment relatively to the barrel when the gun is fired, rings provided on both ends of said casing and having extensions that fit into the intermediate spaces between said ribs on the barrel to close the ends of the annular space between the casing and the barrel substantially air-tight, and a ring fixed to said barrel intermediate of the ends of said casing and substantially filling up the free cross-section between barrel and casing and acting as stationary piston to the reciprocating casing which alternately sucks and expels air through said apertures and renews thus the air surrounding the barrel.

In testimony whereof, I have signed my name to this specification.

ALBERT KÜNG.
